(57) **CLAIM**

The ornamental design for a hinge, as shown and described.

DESCRIPTION

FIG. 1 is a perspective view of the new design for a hinge; FIG. 2 is a top plan view of the new design for a hinge; FIG. 3 is a bottom plan view of the new design for a hinge; FIG. 4 is a front elevational view of the new design for a hinge;

FIG. 5 is a back elevational view of the new design for a hinge;

FIG. 6 is a right elevational view of the new design for a hinge; and,

FIG. 7 is a left elevational view of the new design for a hinge.

The broken lines in the Figures are for illustrative purposes only and form no part of the claimed design.
